UNITED STATES PATENT OFFICE

WILLIAM T. BARRATT, OF BENNINGTON, VERMONT, ASSIGNOR TO CHARLES COOPER COMPANY, INC., OF BENNINGTON, VERMONT, A CORPORATION OF VERMONT

CIRCULAR KNITTING MACHINE

Application filed December 12, 1929. Serial No. 413,593.

This invention relates to improvements in knitting machines, being particularly adapted, although not confined, to use in connection with circular knitting machines of the 5 class in which two rotary circular needle beds are employed for knitting rib work, the same being preferably used in connection with two conical needle beds employing spring needles to produce a rib fabric.

10 The object of the invention is to produce a machine of the character set forth for knitting striped fabric, that is, tubular fabric having stripes of any width or color extending circumferentially therearound.

15 To this end the machine of this invention embodies a plurality of yarn feeds, spaced apart around the needle beds, and each yarn feed embodying therein a single yarn guide, a presser for the primary needles, a sinker 20 wheel for the primary needles, means to cut off and clamp the yarn, and means to throw the yarn guide and the presser for the primary needles out of operative position, and means to at the same time operate the cutting 25 and clamping mechanism.

The invention further contemplates the employment of pattern mechanism whereby any of the feeds may be caused to be thrown into or out of operation, the feeds being 30 thrown into or out of operation by a contact member rotating synchronously with the needle cylinders and positioned to operate upon the different feeds, or thrown out of position so as not to operate upon said feeds by a contact member positioned between each adjacent pair of feeds, said last-named contact members being positioned by means of pattern mechanisms. By the mechanism herein-after described, any one feed or any number 35 of feeds may be selectively caused to be thrown out of operation or thrown into operation and held out of operation or in operation, whereby stripes of any width and different colors may be knitted circumferentially of the tubular knitted fabric.

To these ends the invention consists of the combination and arrangement of parts set forth in the following specification and particularly pointed out in the claims.

Referring to the drawings:

Figure 1 is a plan view partly in section, and somewhat diagrammatic, illustrating one complete feed and the pattern mechanism.

Fig. 2 is a sectional elevation taken on line 2-2 of Fig. 1.

Fig. 3 is a front elevation of one feed, the needle beds, their respective bed plates and running rings being broken away.

Fig. 4 is a detail plan view of one of the feed mechanisms.

Fig. 5 is a detailed elevation of a portion of the mechanism for positioning the switch plate contact member, whereby the driving contact member is thrown into or out of alignment with the rotatable driven contact member.

Fig. 6 is an end elevation of the pattern mechanism viewed in the direction of the arrow *a*, Fig. 1.

Fig. 7 is a side elevation of the pattern 70 mechanism.

Fig. 8 is a front elevation of one of the primary needle operating cams.

Fig. 9 is a sectional elevation taken on line 75 9-9, Fig. 8.

Figs. 10, 11 and 12 are detail views illustrating the operation of the yarn guide and cutters.

Fig. 13 is a detail cross section through the yarn cutters taken on line 13-13, Fig. 10.

Fig. 14 is a sectional elevation illustrating on an enlarged scale the primary and secondary needle beds with the machine doing the ordinary knitting.

Fig. 15 is a similar sectional view showing the needle beds and the needles as they operate when the yarn has been severed and the feed thrown out of operation, there being a presser for the upper needles, the presser 85 for the lower needles not being shown.

Like numerals refer to like parts throughout the several views of the drawings.

In the drawings, 20 is the primary bed, 21 the primary needles and 22 the primary 95 needle cams. The primary needle bed is fastened to a rotary running ring 23 rotatably mounted in a lower bed plate 24 supported upon a stationary frame. A rotary motion is imparted to the running ring 23 and the 100

primary needle bed and its needles by a gear 25 fast to the lower running ring.

26 is the upper or secondary bed, 27 the secondary needles, 27' the secondary needle cams and 28 the upper running ring, to which the secondary bed is fastened. The upper running ring 28 is rotatably mounted in an upper bed plate 29 rigidly supported upon the frame of the machine and is rotated by 10 means of a gear 30 fast to the upper running ring.

An annular cap plate 31 projects over the upper face of the gear 30 and is fastened to the upper bed plate 29. The gears 25 and 30 15 mesh into pinions, not shown in the drawings, but corresponding to the pinions 42 and 53 in applicant's Patent No. 1,003,085, patented September 12, 1911, "Circular knitting machine". A vertical shaft 32, to which said 20 pinions are fastened, is driven by a pulley 33 through a shaft 34 and gearing, substantially as shown and described in said Letters Patent.

Yarn 35 is fed through a guide eye 36, 25 Fig. 3, to a reciprocatory yarn guide 37 and thence the yarn 35 passes into alignment with the sinkers of a sinker wheel 38 rotatably mounted upon a bracket 39, the sinker wheel being rotated by a gear 40 driven by the primary needles 21. The operation of the sinker wheel and its construction are substantially the same as that of the sinker wheel in said 30 Letters Patent.

The beards of the primary needles are 35 pressed by a presser bar 42, which is fastened to a rod 43 slidably in a bracket 44 fast to the lower bed plate 24. The rod 43 has an arm 45 fast thereto and slidably on a rod 46 fast to the bracket 44. Nuts 47 have 40 screw-threaded engagement with the outer end of the rod 46 and between these nuts and the arm 45 a spiral spring 48 is interposed, acting to force the arm 45, rod 43 and presser bar 42 against the primary needles to press 45 their beards in casting off the loops. All of this mechanism is substantially the same as described in said Letters Patent.

The beards of the secondary needles 27 are 50 pressed to cast off their loops by a rotary presser wheel 49, see Fig. 3, which is mounted and operated substantially the same as the presser wheel 32, in said Letters Patent.

The yarn guide 37 is fastened to a slide 50 55 slidably mounted in a bracket 51, see Figs. 2 and 3. The bracket 51 is fastened to the underside of the upper bed plate 29. Said slide 50 has an arm 52 projecting laterally therefrom and connected by an adjustable link 53 to a lever 54 which is pivoted at 55 to a bracket 56 fast to the upper bed plate 29. The opposite end of the lever 54 to that at which the link 53 is connected, engages the under edge of a cam 57 which is fastened to a 60 rotary contact member 58 mounted upon a stud 59 which, in turn, is fastened to the

annular plate 31 and thereby is fastened to the upper bed plate 29. A spring 60 encircles the stud 59 within a recessed portion 61 formed in a hub 62 of the rotary contact member 58 and said spring 61 presses the 70 contact member 58 against the underside of a head 63 of the stud 59, thus providing sufficient friction to prevent the rotary contact member 58 from spinning upon the stud 59.

To the upper face of the rotary contact member 58 are fastened four arms 64, which thus form a part of the contact member 58. An intermittent rotary motion is imparted to the rotary contact member 58 in a manner 80 hereinafter described, and the cam 57 is thus rotated to push the inner end of the lever 54 downwardly, a spring 65 acting to hold the inner end of the lever 54 against the edge of the cam 57. The rotary contact member 85 58 is rotated in the direction of the arrow d, Fig. 4, and the cam 57 will thus push the inner end of the lever 54 downwardly raising the outer end of said lever and through the link 53 and slide 50 the yarn guide 37 will be 90 raised out of operative position, that is, from the position illustrated in Fig. 12 to that illustrated in Fig. 10. In Fig. 12 the yarn is being fed to the needles in alignment with the sinkers 38' of the sinker wheel 38 and between the yarn guide 37 and the needles there is positioned a stationary yarn guard 66; the operation of feeding the yarn to the primary needles by the sinkers being the same as described in said Letters Patent.

When the yarn guide moves from the position illustrated in Fig. 12 to that illustrated in Fig. 10, the yarn 35 is raised out of the path of the sinkers 38' and is cut off and clamped by a movable cutter 67 coacting with a stationary cutter 68, all as set forth in said Letters Patent.

The presser bar 42 is moved outwardly from engagement with the primary needles when the yarn is cut off, in order that the 110 loops on the primary needles may not be cast off, and this movement of the presser bar 42 is accomplished by an arm 69 which is fastened to the lower end of a vertical shaft 70, the free end of the arm 69 bearing against one face of an arm 71 which is rigidly fastened to the arm 45. A rocking motion is 115 imparted to the shaft 70 and the arm 69 by another arm 72 fast to the upper end of the shaft 70, which shaft is rotatably mounted in a bracket 73 fast to the upper bed plate 29.

A rocking motion is imparted to the arm 72 by a cam 74 which forms a part of the rotary contact member 58, so that when motion is imparted to the rotary contact member 58, the cam 74 bearing against the arm 72 will rock it, together with the shaft 70, and arm 69, and thus push the arms 71 and 45, which are in effect one piece, away from the needle cylinder, compressing the spring 48

and through the rod 43 moving the presser bar 42 out of engagement with the primary needles.

A rocking motion is imparted to the movable cutter blade 67 by a cam 75 fast to a bracket 91 on the gear 30, so that as said gear 30 rotates the cam 75 will be brought into engagement with the lower edge 76 of a lever 77 pivoted at 78 to a bracket 79 fast to the upper bed plate. The outer end of the lever 77 is connected by an adjustable link 80 to an arm 81 fast to the movable cutter blade 67. The movable cutter blade is pivoted to a stud 82 fastened to a stationary bracket 83, so that as the lever 77 is rocked upwardly at its inner end, the cutter 67 will be rocked to close the same and cut off the yarn and clamp it to the stationary cutter 68. The cutter 67 is only operated to sever the yarn when the yarn guide has been raised to the position illustrated in Fig. 10 and the yarn is out of alignment with the sinkers and, therefore, the inner end of the lever 77 is normally held upwardly out of the path of the cam 75 by an arm 84 which has an ear 85 projecting normally beneath the inner end of the lever 77, as illustrated in Figs. 3 and 4. The arm 84 is pivotally mounted at 86 to the upper bed plate 29. A spring 87 normally holds the arm 84 with the ear 85 projecting beneath the lever 77, but at the proper time and when it is desired to cut off the yarn, one of the arms 64 of the rotary contact member 58, see Fig. 4, engages a tooth 88 on the free end of the arm 84 and rocks it toward the right, Fig. 4, moving the ear 85 out from under the lever 77 and allowing the inner end of the lever 77 to be moved downwardly by a spring 89, thus bringing the inner end of the lever 77 into alignment with the cam 75 to be operated thereby at the proper time in the rotation of the needle bed, and opening the cutter 67.

An intermittent rotary movement is imparted to the driven contact member 58 by a driving contact member 90, which consists of a pin slidably mounted in a bracket 91 fastened to the gear 30. The pin 90, as illustrated in Fig. 3 is in its lowermost position and when in this position will operate during the rotation of the needle beds and gears to impart an intermittent rotatable movement to the rotary contact member 58 with its arms 64, by reason of the pin 90 contacting with one of the arms 64 and rotating the driven contact member in the direction of the arrow *d*, Fig. 4, a quarter turn.

The driving contact member or pin 90 is raised out of alignment with the arms 64 on the driven contact member 58, or moved down into alignment with said arms by a switch plate 92 constituting a third contact member.

The pin 90 is fastened to a slide 111 slidable vertically in the bracket 91 and is locked in either its upper or lower position by a spring-

actuated pin 112. One of these switch plates, and the mechanism by which it is positioned to move the pin 90 up or down, is provided between each pair of feeds and in the present embodiment of my invention it is intended to use eight feeds positioned at 1, 2, 3, 4, 5, 6, 7 and 8, Fig. 1.

The switch plate 92 is rocked into either of the positions illustrated in Fig. 5 by an arm 93 which is fastened to a shaft 94 mounted in a bracket 95 fast to the stationary ring 31. The switch plate 92 is fastened to the inner end of the rock shaft 94. A rocking movement is imparted to the arm 93 and the rock shaft 94 and switch plate 92 by an arm 96 which is connected by a link 97 to the arm 93, and a rocking movement is imparted to the arm 96 by a shaft 98 mounted in bearings 99 in a bracket 100 which is fastened to the frame 101 of the machine.

The outer end of the shaft 98 has an arm 102 fast thereto which is engaged by a pattern block 103 on the pattern chain 104 so as to raise the free end of the arm 102 and rock the switch plate 92 in one direction. When the block 103 has passed the outer end of the arm 102 said arm will drop and the switch plate will be rocked in the opposite direction. The pattern chain 104 is driven by a pattern wheel 105 in a manner well known to those skilled in this art, and the pattern wheel has fastened thereto a ratchet 106 which is rotated by a pawl 107 and rotates upon a stud 108 fast to the frame of the machine. A reciprocatory motion is imparted to the pawl 107 by an arm 109, to the free end of which it is pivoted at 110.

The arm 109 is fastened to a rock shaft 113 mounted in a bracket 114 fast to the frame of the machine. The inner end of the rock shaft 113 has another arm 115 fast thereto and provided upon its free end with a cam roll 116 adapted to be engaged by a cam 117 fast to the gear 30. The cam roll 116 is held in the path of the cam 117 by a spring 118 fast to the free end of an arm 119 which is in turn fastened to the rock shaft 113. The arm 119 and therefore the arm 115 are limited as to downward movement by the arm 119 contacting with the bracket 114.

Each of the feeds 1, 2, 3, 4, 5, 6, 7 and 8 has a switch plate, and these switch plates are positioned to be engaged by the driving contact member 90, one switch plate in advance of each feed.

120 is the switch plate for number 2 feed and is fastened to the inner end of a rock shaft 126 and is operated by an arm 121, Fig. 6, which is fastened to a rock shaft 122 mounted in the bracket 100 and having fastened to the inner end thereof an arm 123 which is connected by a very fine wire or other flexible member 124 to an arm 125 fast to the rock shaft 126 on a bracket 127 which is fastened to the annular cap plate 31. The

wire 124 is guided to the arm 125 by posts 128 which are provided with annular grooves to receive said wire 124. In this manner the switch plate is tipped into position to raise 5 the driving contact member 90, or to lower the same, by a block on the pattern chain 104.

In the same manner the switch plates, or 10 third contact members for the feeds 3 and 4, are operated by arms 129 and 130 fast to respective shafts 131 and 132 mounted to rock 15 in the bracket 100. The shafts 131 and 132 are provided with arms 133 and 134 respectively, and these arms are connected to arms such as the arms 93 and 125, which rock the 15 switch plates or third contact members 92 and 120 respectively. The switch plates and connections to the same from the arms 129 and 130 are not shown in the drawings, but they are substantially the same as the switch plates 20 92 and 120 and they are operated in substantially the same manner from the arms 129 and 130.

A switch plate or third contact member 135 for feed number 8 is rocked to engage the driving contact member 90 by an arm 136, 25 Fig. 6, which is fastened to a rock shaft 137 mounted to rock in a bracket 138. The inner end of the rock shaft 137 has an arm 139 fastened thereto and connected by a flexible wire 140 guided by post 141 to a rocker arm 142 fast to a rock shaft 143 mounted in a 30 bracket 144 on the ring 31. The switch plate 135 is fast to the inner end of the rock shaft 143 and is operated as hereinbefore described in relation to the switch plates 92 and 120.

35 Arms 145, 146 and 147 are fastened to shafts 148, 149 and 150 respectively, these shafts being mounted to rock in the bracket 138 and being connected to switch plates for the feeds 7, 6 and 5 respectively, in the same 40 manner as hereinbefore described in relation to the connections to the switch plate 135.

The pattern chain 104 is provided with any 45 number of blocks desired. These blocks may be of different widths and positioned as may be desired with relation to the opposite edges of the pattern chain, so that any one of the switch plates may be operated to position the same in the path of the driving contact member in order to raise or lower it, or a block 50 may be of sufficient width to raise a plurality of the arms which operate to position the switch plates. The number of blocks and the width of the blocks on the pattern chain 104 is varied and their positions on the chain laterally and 55 longitudinally thereof may be varied in order to throw the feeds into or out of operation as may be desired for producing stripes of different widths and different colors.

Each feed is provided with a needle cam 60 construction of the character illustrated in Figs. 8 and 9 and embodying therein a stationary needle cam 151 and a vertically movable needle cam 152. Both the cams 151 and 152 are supported on a bracket 153 which is 65 fastened to the lower bed plate 24, and the

cam 152 has fastened thereto a stud 154 and is slidable on a guide way 155 on the bracket 153. An arm 156 is pivoted at 157 to the bracket 153 and is drawn downwardly toward a stop 158 by a spring 159, one end of 70 which is fastened to the free end of the arm 156, the other end being fastened to the lower bed plate 24. The stop 158 consists of an arm which is pivoted at 160 to the bracket 153 and is locked in adjustable position by a 75 screw 161. The movement of the cam 152 downwardly is thus limited by the stop 158. Its movement upwardly is limited by a screw 162 on the bracket 153 and in alignment with the stud 154 which is fastened to the cam 152. Thus the distance to which the cam 152 can be raised or lowered is limited by the stop screw 162 and by the stop arm 158 respectively. 80

The object of the construction illustrated in Figs. 8 and 9 is to hold the cam 152 down 85 with a yielding pressure through the arm 156 and stud 154 and spring 159.

When the machine is doing the regular knitting the yarn is fed first by a sinker wheel 90 to the shanks of the primary needles, they being at this time raised, and at this time there is an old loop on the shank of the primary needle below the loop which is fed to it by the sinker. The loop fed to the primary needle by the sinker, as aforesaid, is long 95 enough to form yarn for a new primary needle loop and a new secondary needle loop, which secondary needle loop the primary needle feeds to the secondary needle when the primary needle is moved down and casts its old 100 loop over the new loop on the primary needle. The secondary needle at this time is down. It has its old loop on the shank and it receives its new loop from the primary needle just above the beard of the secondary needle and 105 below the old loop on the shank of the secondary needle. Now the secondary needle moves up, its beard is pressed to cast off its old loop over its new loop. When this has been done, we have a loop on the primary needle under the beard, and a loop on the secondary needle under the beard, and the primary needle is down and the secondary needle is up. The secondary needle now moves down and its loop moves up on its shank. Then the primary needle comes up and has a loop on its shank. 110

We now come to the next feed. There is no 115 yarn fed at this time to the primary needle and consequently there will be no yarn fed to the secondary needle. The primary needle moves 120 down, but is not pressed, and it has no yarn fed to it as ordinarily, therefore it pulls down its old loop and this pulls down the old loop on the secondary needle and pulls it down under the beard of the secondary needle. 125 This will bring an extra strain to bear upon the yarn, and to compensate for this condition and regulate the tension on the loops so that it will not be excessive, the cam 152 will move up slightly due to the tension of 130

the loops and through the primary needles until a stop screw 162 is engaged by the stud 154. This construction will prevent any extra strain being brought to bear upon the 5 loops of any of the feeds when the yarn is severed as hereinbefore described. In other words, there is strain enough on the yarn to pull the old loop on the secondary needle under its beard. In other words, the one 10 loop on each of the secondary needles is not cast off for the reason that the cam for the primary needles, illustrated in Fig. 18, draws the primary needles down just far enough to cause the old loops on the second- 15 ary needles to be held below the points of the beards of the secondary needles, and when the presser acts on the secondary needles to press the beard into the eye, the old loops on the secondary needles are lower than the 20 point of the beard, and therefore, are retained on the needles, and while the secondary needle is raised into the cast-off position by its cam, this loop is safely under the beard and in the head of the needle.

25 Referring now to Fig. 14, it will be seen that the upper needle 27 has its old loop *a* on its shank above the beard of the needle and is being pressed by the presser 49 to cast off this old loop, the fabric *b* being illustrated as running from the needles up through the secondary needle bed 26. Also, in Fig. 14 the new loop of yarn *c* is being fed to the secondary needles to form a loop *d*, and passes through the old loop *c* which has been cast off the primary needle 21. Then when the presser 49 operates to press the beard of the needle 27, the old loop *a* will be cast off over the new loop *d* which is contained within the beard of the needle 27.

30 In Fig. 15, however, there is no new yarn being fed to the primary needles and by the primary needles to the secondary needles and in this figure it is shown that when the presser 49 operates to close the beard of the needle 27, it will not operate to cast off the loop *d* because that loop is under the beard of the secondary needle and it is under the beard of the secondary needle because the primary needle 21 is pulling down on the loop *c* which 35 at this time is knitted into the fabric *b*. The extra tension which is caused is compensated for in part by the yielding of the primary needle cam 152, as hereinbefore described. Therefore, it will be seen that the primary 40 needle not having cast off its loop *c* and the secondary needle not having cast off its loop *d*, these two loops run to the fabric and are knitted into it, and in order to prevent the 45 yarn from breaking, the cam 152 moves up slightly until the stop screw 162 is engaged by the stop 154.

50 The general operation of the mechanism hereinbefore specifically and to some extent in general described is as follows:—Assuming a feed mechanism such as feed number 1 to be 55 operating to feed yarn to the primary needles, the parts will be in the relative positions illustrated in Figs. 2 and 3; the yarn guide 37 will be in the position illustrated in Fig. 12 and the yarn will then be fed to the 60 primary needles by the sinkers 38; the presser bar 42 will be in position to press the beards of the primary needles 21 to cast off their old loops; the movable cutter blades 67 will be closed and in contact with the stationary cutter blade 68; the driving contact member 90 will be in its upper position and out of alignment with the arms 64 of the 65 driven contact member 58.

When it is desired to sever the yarn and throw the feed number 1 out of operative relation to the needles, the switch plate 92 will be rocked by the arm 102 and connecting mechanism and by a block 103 on the pattern chain from the position illustrated in dotted 70 lines, Fig. 5, to that shown in full lines and the contact pin or driving contact member 90 will engage the underside of the switch plate 92 and be pushed downwardly into its 75 lowermost position, that is, into the position 80 illustrated in Fig. 3.

As the driving contact member 90 rotates synchronously with the needle beds, being mounted in the bracket 91 which is fastened to the gear 30, it follows that as the driving 85 contact member 90 is carried forward in the direction that the beds are rotating, namely, in the direction of the arrow *e*, Fig. 1, the contact 90 will engage one of the arms 64 and rotate the driven contact member 58 in the direction of the arrow *d*, Fig. 4, a quarter turn, this will operate the yarn guide as hereinbefore described and move it from the 90 position illustrated in Fig. 12 to that illustrated in Fig. 10. The movable cutter blade 95 will be opened at this time and the yarn will be drawn in between the movable cutter blade 67 and the stationary cutter blade 68 by reason of the ear 85 on the arm 84 being withdrawn from under the inner end of the lever 77 when one of the arms 64 engages the tooth 88 on said arm 84. The lever 77 being freed at its inner end is drawn downwardly by the spring 89, thus raising the outer end of the lever 77 and momentarily 100 opening the movable cutter blade 67 through the link 80 and arm 81, thus allowing the 105 yarn to be drawn in between the two blades 67 and 68 when the yarn guide 87 is moved upwardly to the position illustrated in Fig. 10. As soon as this has happened the cutter 110 blade 67 is closed by the cam 75 engaging the inner end of the lever 76 and raising the same; thus depressing the link 80 and closing the movable cutter blade 67, severing the 115 yarn and clamping it to the stationary cutter blade 68, and before the cam 75 passes out from beneath the lower edge 76 of the lever 77, said lever 77 is locked against downward movement at its inner end by the arm 120 125

65 feed mechanism such as feed number 1 to be 130

84 which is released by the arm 64 on the driven contact member passing beyond the tooth 88 on said arm 84 and allowing the spring 87 to move the ear 85 under the inner 5 end of the lever 77. The presser bar 42 having been moved outwardly, as hereinbefore set forth, the old loops when the primary needles are moved down at this particular feed will not be cast off, but will be retained 10 thereon.

10 The said feed No. 1 is left out of operation until any number of courses desired have been knit through another feed or feeds, and it is left out of operation by the switch plate 15 92 being tipped from the position shown in full lines, Fig. 5, to the position shown in dotted lines, so that as the contact pin 90 is brought around after the operation hereinbefore described, whereby the feed number 20 1 was thrown out of operative relation with the needles, the said contact pin will engage the switch plate in the position illustrated in dotted lines, Fig. 5, and will be moved upwardly so that as it passes the driven contact member 58 on feed number 1, it will not engage the arm 64 of said driven contact member. In other words, the feed number 25 1 will be left out of operation as long as may be desired.

30 When it is desired to throw it into operation, the third contact member or switch plate 92 will be moved into the position illustrated in Fig. 5, in full lines, and the contact pin 90 will be drawn downwardly to engage 35 an arm 64 of the driven contact member and the operation hereinbefore described, whereby the yarn guide and presser and cutter were operated, will be reversed. The yarn guide will be thrown into operation, the 40 presser will be thrown into operation, the cutter will be opened to release the yarn and the yarn will be carried by the yarn guide first downwardly below its normal position, as illustrated in Fig. 11, thus bringing the 45 yarn into alignment with the sinkers, whereupon it will again move upwardly slightly to the position illustrated in Fig. 12 and the yarn will then be fed to the needles by the sinkers. During this latter operation the 50 yarn guard 66 will prevent the yarn from being carried by the yarn guide down below the sinkers.

It will be seen, therefore, that by employing blocks of different widths, spaced differently with relation to the edges of the pattern chain, and spaced as may be desired longitudinally of the pattern chain, any desired combination may be obtained whereby 55 stripes of different widths and of different 60 colors may be knitted in a tubular fabric by the machine hereinbefore described.

I claim:

1. A circular spring needle knitting machine having, in combination, a rotary circular needle bed, spring needles thereon, a plu- 65

rality of feed mechanisms spaced apart around said bed to feed yarn to said needles, each feed mechanism embodying a single yarn guide, a sinker wheel, a presser member adapted to be engaged by said needles as they are carried along by said needle bed and a driven contact member, means operated by each of said driven contact members to throw its respective yarn guide and presser member into or out of operative position, a driving contact member rotatable synchronously with said needle bed and adapted to engage and operate said driven contact members for the purpose aforesaid, and mechanism to move said driving contact member into or out of the path of said driven contact members. 70 75 80

2. A circular spring needle knitting machine having, in combination, a rotary circular needle bed, spring needles thereon, a plurality of feed mechanisms spaced apart around said bed to feed yarn to said needles, each feed mechanism embodying a single yarn guide, a sinker wheel, a presser member and a driven contact member, means operated by each of said driven contact members to throw its respective yarn guide and presser member into or out of operative position, a driving contact member rotatable synchronously with said needle bed and adapted to engage and operate said driven contact members for the purpose aforesaid, a third contact member for each feed mechanism adapted to be engaged by said driving contact member during its rotation, and the latter thereby positioned in or out of the path of said driven contact members, and mechanism to position said third contact members in or out of the path of said driving contact member. 85 90 95 100

3. A circular spring needle knitting machine having, in combination, a rotary circular needle bed, spring needles thereon, a plurality of feed mechanisms spaced apart around said bed to feed yarn to said needles, each feed mechanism embodying a single yarn guide, a sinker wheel, a presser member and a driven contact member, means operated by each of said driven contact members to throw its respective yarn guide and presser member into or out of operative position, a driving contact member rotatable synchronously with said needle bed and adapted to engage and operate said driven contact members for the purpose aforesaid, a third contact member positioned between each pair of feed mechanisms respectively and adapted to be engaged by said driving contact member during its rotation, and the latter thereby positioned in or out of the path of the next succeeding driven contact member, and pattern mechanism to position each of said third contact members respectively in or out of the path of said driving contact member. 110 115 120 125 130

4. A circular spring needle knitting ma-

- chine having, in combination, a rotary circular needle bed, spring needles thereon, a plurality of feed mechanisms spaced apart around said needle bed to feed yarn to said needles, each feed mechanism embodying a single yarn guide, a sinker wheel, a needle presser adapted to be engaged by said needles as they are carried along by said needle bed, and a rotatable driven contact member, cams on said rotatable driven contact member, and means connected to said yarn guide and to said presser and operable by said rotatable driven contact member cams to move said yarn guide and presser into and out of operative position relatively to the needles.
5. A circular spring needle knitting machine having, in combination, a rotary circular needle bed, spring needles thereon, a plurality of feed mechanisms spaced apart around said needle bed to feed yarn to said needles, each feed mechanism embodying a single yarn guide, a sinker wheel and a needle presser adapted to be engaged by said needles as they are carried along by said needle bed, a rotatable driven contact member, cams on said rotatable driven contact member, means connected to said yarn guide and to said needle presser and operable by said rotatable driven contact member to move said yarn guide and needle presser into and out of operative position relatively to the needles, a driving contact member rotatable synchronously with said needle bed and adapted to engage and impart to said rotatable driven contact members and cams an intermittent rotary motion, a third contact member for each feed mechanism adapted to be engaged by said driving contact member during its rotation and the latter thereby positioned in or out of the path of said rotatable driven contact members, and pattern mechanism to position said third contact members in or out of the path of said driving contact member.
6. A circular spring needle knitting machine having, in combination, a rotary circular needle bed, spring needles thereon, a plurality of feed mechanisms spaced apart around said needle bed to feed yarn to said needles, each feed mechanism embodying a single yarn guide, a sinker wheel and a needle presser adapted to be engaged by said needles as they are carried along by said needle bed, a rotatable driven contact member, cams on said rotatable driven contact member, means connected to said yarn guide and to said needle presser and operable by said rotatable driven contact member cams to move said yarn guide and presser into and out of operative position relatively to the needles, a driving contact member rotatable synchronously with said needle bed and adapted to engage and impart to said rotatable driven contact members and cams an intermittent rotary motion, and mechanism to move said driving contact member into or out of the path of said rotatable driven contact members.
7. A circular spring needle knitting machine having, in combination, a rotary circular needle bed, spring needles thereon, a plurality of feed mechanisms spaced apart around said needle bed to feed yarn to said needles, each feed mechanism embodying a single yarn guide, a sinker mechanism and needle pressing means, a rotatable driven contact member, cams on said rotatable driven contact member, means connected to said yarn guide and to said pressing means and operable by said rotatable driven contact member to move said yarn guide and pressing means into and out of operative position relatively to the needles, a driving contact member rotatable synchronously with said needle bed and adapted to engage and impart to said rotatable driven contact members and cams an intermittent rotary motion, and a third contact member for each feed mechanism adapted to be engaged by said driving contact member during its rotation and the latter thereby positioned in or out of the path of said rotatable driven contact members.
8. A circular spring needle knitting machine having, in combination, a rotary circular needle bed, spring needles thereon, a plurality of feed mechanisms spaced apart around said needle bed to feed yarn to said needles, each feed mechanism embodying a single yarn guide, a sinker wheel, a needle presser adapted to be engaged by said needles as they are carried along by said needle bed, and a rotatable driven contact member, means connected to said yarn guide and to said presser and operable by said rotatable driven contact member to move said yarn guide and presser into and out of operative position relatively to the needles, a yarn cutter, and mechanism to operate the same including a cam rotatable synchronously with said needle bed.
9. A circular spring needle knitting machine having, in combination, a rotary circular needle bed, spring needles thereon, a plurality of feed mechanisms spaced apart around said needle bed to feed yarn to said needles, each feed mechanism embodying a single yarn guide, a rotatable driven contact member, means connected to said yarn guide and operable by said driven contact member to move said yarn guide into and out of operative position relatively to the needles, a driving contact member rotatable synchronously with said needle bed and adapted to engage and impart to said rotatable driven contact member an intermittent rotary motion, a yarn cutter, mechanism to operate the same including a cam rotatable synchronously with said needle bed, and means operable by said driving contact member to render said

- yarn cutter mechanism operable or inoperable by said rotatable cam.
10. A circular spring needle knitting machine having, in combination, a rotary circular needle bed, spring needles thereon, a plurality of feed mechanisms spaced apart around said needle bed to feed yarn to said needles, each feed mechanism embodying a single slidable yarn guide, a rotatable driven contact member, and means connected to said yarn guide and operable by said rotatable driven contact member to slide said yarn guide into and out of operative position relatively to said needles.
15. 11. A circular spring needle knitting machine having, in combination, a rotary circular needle bed, spring needles thereon, a plurality of feed mechanisms spaced apart around said needle bed to feed yarn to said needles, each feed mechanism embodying a single slidable yarn guide, sinker mechanism and slidable needle pressing means, a rotatable driven contact member, means connected to said yarn guide, and means connected to said pressing means and operable by said rotatable driven contact member to slide said yarn guide and pressing means into and out of operative position relatively to said needles.
20. 12. A circular spring needle knitting machine having, in combination, a rotary circular needle bed, spring needles thereon, a plurality of feed mechanisms spaced apart around said needle bed to feed yarn to said needles, each feed mechanism embodying a single yarn guide, sinker mechanism, needle pressing means, and a rotatable driven contact member, means connected to said yarn guide and to said pressing means and operable by said rotatable driven contact member to move said yarn guide and pressing means into and out of operative position relatively to the needles, a driving contact member rotatable synchronously with said needle bed, a yarn cutter, mechanism to operate the same including a cam rotatable synchronously with said needle bed, a lever, and means normally engaging said lever and holding it out of the path of said cam, said lever-engaging means being operable by said driving contact member to release said lever and allow it to move into the path of said cam, whereby said yarn cutter mechanism may be operated.
25. 13. A circular spring needle knitting machine having, in combination, a rotary circular needle bed, spring needles thereon, a plurality of feed mechanisms spaced apart around said bed to feed yarn to said needles, each feed mechanism embodying a single yarn guide, a sinker wheel, a presser member and a driven contact member, means operated by each of said driven contact members to throw its respective yarn guide and presser member into or out of operative position, a driving contact member rotatable synchronously with said needle bed and adapted to engage and operate said driven contact members for the purpose aforesaid, a third contact member for each feed mechanism comprising a switch plate adapted to be engaged by said driving contact member during its rotation and the latter thereby positioned in or out of the path of said driven contact members, a pattern mechanism, and connections therefrom to said switch plates whereby the latter may be rocked into or out of the path of said driving contact member.
30. 14. A circular spring needle knitting machine having, in combination, a circular needle bed and needles, a series of yarn feeds disposed about said bed and spaced apart, each of said feeds embodying therein a single yarn guide, a needle presser adapted to be engaged by said needles as they are carried by said needle bed, and mechanism, including a driven contact member, to throw said yarn guide and presser into and out of operative relation to said needles, and a driving contact member rotatable synchronously with said needle bed and adapted to engage and operate said driven contact members for the purpose specified.
35. 15. A circular spring needle knitting machine having, in combination, a circular needle bed and needles, a series of yarn feeds disposed about said bed and spaced apart, each of said feeds embodying therein a single yarn guide, a needle presser member and mechanism, including a driven contact member, to throw said yarn guide and presser member into and out of operative relation to said needles, a driving contact member rotatable synchronously with said needle bed, and pattern actuated contact means provided in advance of each of said feeds respectively and adapted to be engaged by said driving contact member and thereby position the latter in or out of the path of said driven contact members and said driven contact members operated or not operated thereby respectively for the purpose specified.
40. 16. A circular spring needle knitting machine having, in combination, a circular needle bed and needles, a series of yarn feeds disposed about said bed and spaced apart, each of said feeds embodying therein a single yarn guide, a needle presser member and mechanism, including a driven contact member, to throw said yarn guide and presser member into and out of operative relation to said needles, a driving contact member rotatable synchronously with said needle bed, a third contact member provided in advance of each of said feeds respectively, pattern means, and connections from said pattern means to each of said third contact members respectively and adapted to position the latter to be engaged by said driving contact member and the latter thereby caused to be moved into

or out of the path of said driven contact members and the latter operated or not operated thereby respectively for the purpose specified.

5 17. A circular spring needle knitting machine having, in combination, a rotary circular needle bed, spring needles thereon, a plurality of feed mechanisms spaced apart around said needle bed to feed yarn to said needles, each feed mechanism embodying a single yarn guide, sinker mechanism, needle pressing means, and a rotatable driven contact member, means connected to said yarn guide and to said pressing means and operable by said rotatable driven contact member to move said yarn guide and pressing means into and out of operative position relatively to the needles, a needle cam at each of said feeds, and a spring actuating said needle cam, said cam adapted to be moved upwardly by the needles against the tension of said spring, whereby tension on the loops of yarn which are on the needles may be regulated.

10 18. A circular spring needle knitting machine having, in combination, a rotary circular needle bed, spring needles thereon, a plurality of feed mechanisms spaced apart around said needle bed to feed yarn to said needles, each feed mechanism embodying a single yarn guide, sinker mechanism, needle pressing means, and a rotatable driven contact member, means connected to said yarn guide and to said pressing means and operable by said rotatable driven contact member to move said yarn guide and pressing means into and out of operative position relatively to the needles, a vertically slideable needle cam at each of said feeds, a spring-actuated lever connected to each of said cams respectively, and means to limit the movement of said levers whereby the tension on the loops may be regulated.

19. A circular spring needle rib knitting machine having, in combination, a primary rotary circular needle bed, a secondary circular rotary needle bed, spring needles on each of said rotary needle beds, a plurality of feed mechanisms spaced apart around said beds to feed yarn to the primary needles, each feed mechanism embodying a single yarn guide, a sinker wheel, a presser member for the primary needles adapted to be engaged by said primary needles as they are carried along by the primary needle bed, a presser member for the secondary needles adapted to be engaged by said secondary needles as they are carried along by said secondary needle bed and a driven contact member, means operated by each of said driven contact members to throw its respective yarn guide and the presser member for the primary needles into or out of operative position, and a driving contact member rotatable synchronously with said needle beds and adapted to engage and

operate said driven contact members for the purpose aforesaid.

20. A circular spring needle rib knitting machine having, in combination, a primary rotary circular needle bed, a secondary circular rotary needle bed, spring needles on each of said rotary needle beds, a plurality of feed mechanisms spaced apart around said beds to feed yarn to the primary needles, each feed mechanism embodying a single yarn guide, a sinker wheel, a presser member for the primary needles, a presser member for the secondary needles and a driven contact member, means operated by each of said driven contact members to throw its respective yarn guide and the presser member for the primary needles into or out of operative position, a driving contact member rotatable synchronously with said needle beds and adapted to engage and operate said driven contact members for the purpose aforesaid, and mechanism to move said driving contact member into or out of the path of said driven contact members.

21. A circular spring needle rib knitting machine having, in combination, a primary rotary circular needle bed, a secondary circular rotary needle bed, spring needles on each of said rotary needle beds, a plurality of feed mechanism spaced apart around said beds to feed yarn to the primary needles, each feed mechanism embodying a single yarn guide, a sinker wheel, a presser member for the primary needles, a presser member for the secondary needles and a driven contact member, means operated by each of said driven contact members to throw its respective yarn guide and the presser member for the primary needles into or out of operative position, and a driving contact member rotatable synchronously with said needle beds and adapted to engage and operate said driven contact members for the purpose aforesaid, and a third contact member for each feed mechanism adapted to be engaged by said driving contact member during its rotation, and the latter thereby positioned in or out of the path of said driven contact members.

22. A circular spring needle rib knitting machine having, in combination, a primary rotary circular needle bed, a secondary circular rotary needle bed, spring needles on each of said rotary needle beds, a plurality of feed mechanisms spaced apart around said beds to feed yarn to the primary needles, each feed mechanism embodying a single yarn guide, a sinker wheel, a presser member for the primary needles, a presser member for the secondary needles and a driven contact member, means operated by each of said driven contact members to throw its respective yarn guide and the presser member for the primary needles into or out of operative position, and a driving contact member rotatable synchronously with said needle beds and adapted to engage and

10 synchronously with said needle beds and adapted to engage and operate said driven contact members for the purpose aforesaid, a third contact member for each feed mechanism adapted to be engaged by said driving contact member during its rotation, and the latter thereby positioned in or out of the path of said driven contact members, and mechanism to position said third contact members in or out of the path of said driving contact member.

23. A circular spring needle rib knitting machine having, in combination, a primary rotary circular needle bed, a secondary circular rotary needle bed, spring needles on each of said rotary needle beds, a plurality of feed mechanisms spaced apart around said beds to feed yarn to the primary needles, each feed mechanism embodying a single yarn guide, a sinker wheel, a presser member for the primary needles, a presser member for the secondary needles and a driven contact member, means operated by each of said driven contact members to throw its respective yarn guide and the presser member for the primary needles into or out of operative position, a driving contact member rotatable synchronously with said needle beds and adapted to engage and operate said driven contact members for the purpose aforesaid, a third contact member positioned between each pair of feed mechanisms respectively and adapted to be engaged by said driving contact member during its rotation and the latter thereby positioned in or out of the path of the next succeeding driven contact member, and mechanism to position each of said third contact members respectively in or out of the path of said driving contact member.

24. A circular spring needle knitting machine having, in combination, a primary rotary circular needle bed, a secondary circular rotary needle bed, spring needles on each of said rotary needle beds, a plurality of feed mechanisms spaced apart around said needle beds to feed yarn to the primary needles, each feed mechanism embodying a single yarn guide, sinker mechanism for the primary needles, a needle presser for the primary needles adapted to be engaged by said primary needles as they are carried along by said primary needle bed, a needle presser for the secondary needles adapted to be engaged by said secondary needles as they are carried along by said secondary needle bed, and a rotatable driven contact member, cams on said rotatable driven contact member, and means connected to said yarn guide and to the presser for the primary needles and operable by said rotatable driven contact member cams to move said yarn guide and the pressing means for the primary needles into and out of operative position relatively to the needles, a driving contact member rotatable synchronously with said needle beds and adapted to engage and impart to said rotatable driven contact members and cams an intermittent rotary motion, and mechanism to move said driving contact member into or out of the path of said rotatable driven contact members.

25. A circular spring needle knitting machine having, in combination, a primary ro-

70 tary circular needle bed, a secondary circular rotary needle bed, spring needles on each of said rotary needle beds, a plurality of feed mechanisms spaced apart around said needle beds to feed yarn to the primary needles, each feed mechanism embodying a single yarn guide, sinker mechanism for the primary needles, a needle presser for the primary needles, adapted to be engaged by said primary needles as they are carried along 75 by said primary needle bed, a needle presser for the secondary needles adapted to be engaged by said secondary needles as they are carried along by said secondary needle bed and a rotatable driven contact member, cams on said rotatable driven contact member, means connected to said yarn guide and to the pressing means for the primary needles and operable by said rotatable driven contact member cams to move said yarn guide and 80 the pressing means for the primary needles into and out of operative position relatively to the needles, and a driving contact member rotatable synchronously with said needle beds and adapted to engage and impart to said 85 rotatable driven contact members and cams an intermittent rotary motion.

26. A circular spring needle knitting machine having, in combination, a primary rotary circular needle bed, a secondary circular rotary needle bed, spring needles on each of said rotary needle beds, a plurality of feed mechanisms spaced apart around said needle beds to feed yarn to the primary needles, each feed mechanism embodying a single yarn guide, sinker mechanism for the primary needles, needle pressing means for the primary needles, needle pressing means for the secondary needles and a rotatable driven contact member, cams on said rotatable driven contact member, means connected to said yarn guide and to the pressing means for the primary needles and operable by said rotatable driven contact member cams to move said 90 yarn guide and the pressing means for the primary needles into and out of operative position relatively to the needles, a driving contact member rotatable synchronously with said needle beds and adapted to engage and impart to said rotatable driven contact members and cams an intermittent rotary motion.

100 105 110 115 120 125 130

27. A circular spring needle knitting machine having, in combination, a primary rotary circular needle bed, a secondary circular rotary needle bed, spring needles on each of said rotary needle beds, a plurality of feed mechanisms spaced apart around said beds to feed yarn to the primary needles, each feed mechanism embodying a single yarn guide, sinker mechanism for the primary needles, needle pressing means for the primary needles, needle pressing means for the secondary

needles and a rotatable driven contact member, means connected to said yarn guide and to said primary needle pressing means and operable by said rotatable driven contact member to move said yarn guide and pressing means for the primary needles into and out of operative position relatively to the needles, and a needle cam at each of said feeds, and a spring actuating said needle cam, said cam adapted to be moved upwardly by the needles against the tension of said spring, whereby tension on the loops of yarn which are on the needles may be regulated.

28. A circular spring needle knitting machine having, in combination, a primary rotary circular needle bed, a secondary circular rotary needle bed, spring needles on each of said rotary needle beds, a plurality of feed mechanisms spaced apart around said beds to feed yarn to the primary needles, each feed mechanism embodying a single yarn guide, sinker mechanism for the primary needles, needle pressing means for the primary needles, needle pressing means for the secondary needles, and a rotatable driven contact member, means connected to said yarn guide and to said primary needle pressing means and operable by said rotatable driven contact member to move said yarn guide and pressing means for the primary needles into and out of operative position relatively to the needles, a driving contact member rotatable synchronously with said needle beds and adapted to engage and impart to said rotatable driven contact members an intermittent rotary motion, a yarn cutter, mechanism to operate the same including a cam rotatable synchronously with said needle beds, and means operable by said driving contact member to render said yarn cutter mechanism operable or inoperable by said rotatable cam.

29. A circular spring needle rib knitting machine having, in combination, a primary rotary circular needle bed, spring needles thereon, a secondary circular rotary needle bed and spring needles thereon, a plurality of feed mechanism spaced apart around said needle beds to feed yarn to the primary needles, each feed mechanism embodying a single yarn guide, sinker mechanism, a presser member for the primary needles, a presser member for the secondary needles and a rotatable driven contact member, means connected to said yarn guide and to said presser member for the primary needles and operable by said rotatable driven contact member to move said yarn guide and the presser member for the primary needles into and out of operative position relatively to the primary needles, a yarn cutter, and mechanism to operate the same including a cam rotatable synchronously with said needle beds.

30. A circular spring needle knitting machine having, in combination, a primary ro-

tary circular needle bed, a secondary circular rotary needle bed, spring needles on each of said rotary needle beds, a plurality of feed mechanisms, spaced apart around said needle beds, to feed yarn to the primary needles, each feed mechanism embodying a single yarn guide, sinker mechanism, needle pressing means for the primary needles, needle pressing means for the secondary needles, a rotatable driven contact member, means connected to said yarn guide and to said pressing means for the primary needles and operable by said rotatable driven contact member to move said yarn guide and the pressing means for the primary needles into and out of operative position relatively to the needles, a driving contact member rotatable synchronously with said needle beds and adapted to engage and impart to said rotatable driven contact members an intermittent rotary motion, a yarn cutter, mechanism to operate the same including a cam rotatable synchronously with said needle beds, and means operable by said driving contact member to render said yarn cutter mechanism operable or inoperable by said rotatable cam.

31. A circular spring needle knitting machine having, in combination, a primary rotary circular needle bed, a secondary circular rotary needle bed, spring needles on each of said rotary needle beds, a plurality of feed mechanisms spaced apart around said needle beds to feed yarn to said primary needles, each feed mechanism embodying a single yarn guide, a rotatable driven contact member, means connected to said yarn guide and operable by said rotatable driven contact member to move said yarn guide into and out of operative position relatively to the primary needles, a driving contact member rotatable synchronously with said needle beds and adapted to engage and impart to said rotatable driven contact member an intermittent rotary motion, a yarn cutter, mechanism to operate the same including a cam rotatable synchronously with said needle beds, and means operable by said driving contact member to render said yarn cutter mechanism operable or inoperable by said rotatable cam.

In testimony whereof I have hereunto set my hand.

WILLIAM T. BARRATT.
